BOTTLE CARRIER.

Harry Z. Gray, Lebanon, Ohio

Application September 9, 1937, Serial No. 163,019

3 Claims. (Cl. 224—45)

This invention relates to bottle carriers, and more especially it relates to bottle carriers that support bottles solely by engagement with the necks thereof.

3. The chief objects of the invention are to provide extreme simplicity of construction; to effect economy of material; to provide a carrier that easily and quickly may be attached to the bottles, and as readily be disengaged therefrom;

10. to provide a carrier that cannot accidentally become disengaged from the bottles; and to provide a carrier of the character mentioned that may be re-used a number of times. In general the invention aims to provide an attractive and efficient bottle carrier that is inexpensive, and that occupies relatively small space when not in use. Other objects will be manifest as the specification proceeds.

Of the accompanying drawing:

20 Fig. 1 is a side elevation of the improved bottle carrier, and a plurality of bottles operatively associated therewith;

Fig. 2 is an end elevation thereof;

Fig. 3 is an end elevation thereof, Fig. 3 is a section, on a larger scale, on the line 3—3 of Figure 1; and

Fig. 4 is a plan view of a portion of the bottle carrier showing how a pair of openings therein are positioned in offset relation to each other to cause the carrier to grip a bottle neck.

30 Referring to the drawing, it will be seen that the improved carrier is composed of two identical blanks 10, 10, which blanks are composed of heavy cardboard or other stiff, foldable material. Each of said blanks is folded or doubled 35 upon itself, longitudinally near its middle, as indicated at 11, 11. The folded blanks, disposed in face to face relation, are permanently secured to each other by a plurality of rivets 12, 12 that extend through the four plies of card- 40 board about midway between the folded margins 11 of the blanks and the free margins at the side opposite said folded margins. Between the rivets 12 and the folded margins 11 the structure is formed with an elongate aperture 45 13 of sufficient size to receive four fingers of the hand, the four-ply portion thus constituting a hand-grip for the carrier.

Both plies or leaves of each folded blank 10 are longitudinally creased or scored along the line 15, which is located immediately below the rivets 12, to the end that the free, lower parts of the plies may be flexed along these lines. As shown in the drawing, the plies of one blank are flexed in opposite direction to the plies of the other blank, and constitute flaps. The flaps

of each blank are designated 16 and 17 of which the flaps 16 are a part of the outermost ply of each blank, and are uppermost when the carrier is in use as shown.

Each of the flaps 17 is formed with one or more circular apertures 19, herein shown as three in number, there being an even half dozen in the two flaps and the apertures in one flap being in alignment with the apertures in the other flap transversely of the carrier. Each aperture 19 is of the proper diameter to permit the cap 20 and enlarged bead 21 at the top of a bottle 22 to pass easily but not loosely therethrough, the aperture being somewhat larger than the neck of the bottle. Preferably the margins of the apertures 19 are reinforced or stiffened, as by the cardboard rings 23 adhered thereabout, although any other suitable reinforcing means may be used.

Each of the flaps 16 is formed with one or 20 more apertures 25 corresponding in number to the apertures 19. The apertures 25 are in the form of slots that have rounded ends of the same radius as the apertures 19, the width of the slots being the same as the diameter of said apertures. The long axis of each of the slots 25 is disposed transversely of the flap 16, and intersects the axis of an underlying aperture 19. The slots 25 may be reinforced with cardboard 26 in the same manner as the apertures 19. 30

When a flap 16 and its companion flap 17 are in juxtaposition as shown, the apertures 19 and the slots 25 are in offset relation to each other in the direction of the long axis of the slots, the imperforate portion of the flaps 16, at 35 the inner ends of slots 25, overlying a small portion of each aperture 19 so that the through openings defined by the apertures and slots are of oblate form in the direction of the long axis of the slots, as is clearly shown in Fig. 4 of the 40 drawing. Furthermore, the extent to which the flaps 16 overlie the apertures 19 varies according to the angle at which the flaps 16, 17 stand with relation to the hand-grip portion of the carrier, and come closer to alignment as the flaps swing 45 downwardly this being due to the fact that flaps 17 extend around a longer arc at the hinge 15.

In the operation of applying the carrier to a group of bottles, the upper flaps 16 are bent upwardly and backwardly against the hand-grip portion and held there. The lower flaps 17 are then slipped over the bottles 22 as far as the necks thereof, the caps 20 and beads 21 of the bottles passing readily through apertures 19. The flaps 16 are then released and bent down 55

over the bottles until they rest against flaps 17, the upper ends of the bottles passing readily through the slots 25. Now when the carrier is lifted, slight relative movement between the flaps 16, 17 causes the neck of each bottle to be engaged on one side by the marginal wall of an aperture 19 and on the diametrically opposite side by the marginal wall at the inner end of a slot 25. The arrangement is most clearly illustrated in Fig. 4 wherein the perimeter of a bottle neck is indicated by a dot and dash line. The weight of the bottles assures that the necks thereof will be tightly gripped, and the enlarged bead 21 on the bottles avoids any possibility of accidental release of the latter.

Although the blanks 10 are duplicates of each other and each alone would function in the manner described, it is preferable to use two of the blanks assembled back-to-back as shown for the reason that the bottles 22 will then abut each other and be suspended in vertical position. If but one blank were used the bottle or bottles therein would hang at an angle to the hand-grip portion of the carrier and would be somewhat awkward to handle. Preferably the spacing of the apertures 19 and slots 25 longitudinally of the carrier is such that the bottles carried therein abut each other. The arrangement avoids rattling of the bottles against each other and reduces the possibility of breakage from this cause.

The improved carrier may be used many times since it does not require to be mutilated to remove the bottles therefrom. When not in use the flaps 16, 17 will lie in the same plane as the hand-grip portion of the carrier, thus conserving space during storage or shipment. The device is simple and economical, and achieves the other advantages set out in the foregoing statement of objects.

Modification may be resorted to without departing from the spirit of the invention, or the scope thereof as defined by the appended claims.

What is claimed is:

1. In a bottle carrier for bottles having beaded cap-receiving upper ends, a hand grip portion and a pair of flaps hinged to said hand grip portion independently of each other along the same margin thereof, each of said flaps being formed with an aperture of larger size than the bead-end of a bottle so as to enable the said bead to pass therethrough, said apertures being so arranged as to be overlapping when the flaps are side-by-side and thereby together to define a through opening in the flaps of smaller size than the bead portion of a bottle but larger than the adjacent neck of the bottle, the flaps being sepa-

rately angularly movable upon their hinges to enable separation of the flaps whereby the bead portion of a bottle may be passed through the respective apertures in succession.

2. In a bottle carrier for bottles having beaded cap-receiving upper ends, a hand grip portion and two pairs of flaps of which each flap is independently hinged to said hand grip portion along the same margin thereof, each pair of flaps being capable of limited common angular movement relatively of the hand grip portion and the flaps of each pair having limited angular movement relatively of each other, the flaps of the respective pairs of flaps being inclined in the same general direction, the pairs of flaps being in diverging relation to each other, the flaps of each pair having openings therein of larger size than the bead end of a bottle and, when in juxtaposition, defining a bottle-neck-receiving opening of smaller size than the bead-end of a bottle, whereby a bottle may be suspended therein, the opening in one pair of flaps being in alignment with the opening in the other pair of flaps, transversely of the carrier, so that bottles suspended from the two pairs of flaps laterally abut each other and thereby are maintained in vertical position.

3. A bottle carrier formed of relatively stiff material comprising a hand grip portion arranged to extend in a generally vertical direction when in use, carrying flaps hinged to the lower margin of the hand grip portion independently of each other along parallel hinge lines and arranged to extend in a generally lateral direction from the hand grip portion, said flaps being adapted to assume a position in relatively close superposed relation and to be capable of limited common angular movement relatively of the hand grip portion when so positioned, and also capable of limited angular movement relatively of each other, each flap being formed with an aperture of sufficient size to freely admit the neck of a bottle, the aperture in the overlying flap being offset outwardly with respect to the aperture of the underlying flap so that the edge of the aperture of the overlying flap adjacent its hinge is adapted to engage against one side of the bottle neck and the edge of the aperture of the underlying flap remote from its hinge is adapted to engage the opposite side of the bottle neck, whereby, when the bottle neck has been inserted through both apertures and the flaps brought into relatively close, superposed relation, the neck of the bottle will be snugly engaged by the edges of said openings.
